US00D618240S

(12) **United States Design Patent**
Larmour et al.

(10) **Patent No.:** **US D618,240 S**
(45) **Date of Patent:** **** Jun. 22, 2010**

(54) **WIRELESS ADAPTER**

(75) Inventors: **David W. Larmour**, Suwanee, GA (US);
Hyun H. Lee, Atlanta, GA (US);
Bradley J. Wolf, Glenview, IL (US)

(73) Assignee: **Motorola, Inc.**, Schaumburg, IL (US)

(**) Term: **14 Years**

(21) Appl. No.: **29/328,768**

(22) Filed: **Dec. 2, 2008**

(51) **LOC (9) Cl.** **14-02**

(52) **U.S. Cl.** **D14/358; D14/230**

(58) **Field of Classification Search** **D14/137, D14/167, 168, 230, 231, 233, 235, 237, 240–242, D14/299, 432, 435, 436, 155, 496, 300–302, D14/313, 314, 214, 348–363, 365–370; D18/56; D13/149, 162, 184, 199; D3/201, 273, 203.6, D3/247, 264, 265; D27/186, 189; D9/420, D9/423, 432; 312/223.1, 223.2; 369/34.01, 369/36.01, 272.1; 360/132, 133, 135; 361/679.31–679.45; D28/83; D6/407, 632**

See application file for complete search history.

Primary Examiner—Cathron C Brooks

Assistant Examiner—Karen E Kearney

(57) **CLAIM**

The ornamental design for a wireless adapter, as shown and described.

DESCRIPTION

FIG. 1 is a perspective view of an ornamental design for a wireless adapter;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines shown in FIGS. 1–7 are for the purpose of illustrating environmental structure and form no part of the claimed design.

1 Claim, 4 Drawing Sheets
